(57) **CLAIM**

The ornamental design for a customer facing kiosk, substantially as shown and described.

DESCRIPTION

FIG. 1 is a perspective view of a customer facing kiosk, showing our new design;

FIG. 2 is a front elevation view thereof.

FIG. 3 is a left elevation view thereof.

FIG. 4 is a right elevation view thereof.

FIG. 5 is a top plan view thereof.

FIG. 6 is a bottom plan view thereof.

FIG. 7 is a back elevation view thereof.

FIG. 8 is a zoom in view of the light pipe around the customer facing kiosk; and,

FIG. 9 is a perspective view of an alternative embodiment of the customer facing kiosk with a side attachment, in which other views remain the same as in prior figures.

1 Claim, 5 Drawing Sheets
